Primary Examiner—Sandra Snapp(74) *Attorney, Agent, or Firm*—Cantor Colburn LLP(57) **CLAIM**

We claim, the ornamental design for a diffusing evaporator of active substances, as shown and described.

DESCRIPTION

FIG. 1 is a top perspective view diffusing evaporator of active substances showing our new design;

FIG. 2 is front elevation view thereof;

FIG. 3 is a top plan view thereof;

FIG. 4 is a side elevation view thereof;

FIG. 5 is a rear elevation view thereof;

FIG. 6 is a bottom plan view thereof; and,

FIG. 7 is a side elevation opposite that shown in FIG. 4.

The broken lines shown in the drawings are for illustrative purposes only and form no part of the claimed design.
